UNITED STATES PATENT OFFICE.

WALTER L. BOCKOVER, OF TIPTON, INDIANA, ASSIGNOR OF ONE-THIRD TO JOHN W. McNAMARA AND ONE-THIRD TO HENRY J. O'NEILL, BOTH OF TIPTON, INDIANA.

PIPE WRENCH.

1,407,691.

Specification of Letters Patent. Patented Feb. 28, 1922.

Application filed September 15, 1921. Serial No. 500,749.

To all whom it may concern:

Be it known that I, WALTER L. BOCKOVER, a citizen of the United States, residing at Tipton, in the county of Tipton and State of Indiana, have invented a new and useful Pipe Wrench, of which the following is a specification.

This invention relates to tools, and more particularly to adjustable pipe wrenches, the primary object of the invention is to provide a wrench which will be automatically adjusted to grip an article, when pressure is brought to bear on the handle thereof. Another object of the invention is to provide a wrench wherein the jaws will be forced into closer gripping relation with the article under operation as the pressure on the handle portion of the tool is increased.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:—

Figure 1 is a side elevational view of a wrench constructed in accordance with the present invention, a portion of the handle being broken away to illustrate the connection between the inner jaw and handle.

Figure 2 is a fragmental rear elevational view of the wrench.

Referring to the drawing in detail, the reference character 5 designates the handle portion of the wrench which has one end thereof bifurcated to provide spaced arms 6, the outer ends thereof being offset as at 7 for purposes to be hereinafter more fully described.

The spaced arms 6 provide a support for the inner jaw 8 which is positioned between the arms in a manner to restrict lateral movement of the jaw with respect to the handle, but permit of pivotal movement of the jaw.

This jaw 8 is provided with an elongated opening 9 designed to accommodate the pin 10, which extends through suitable openings provided in the arms 6 and provides the pivot for the inner jaw 8. The outer jaw,

which is indicated at 11 embodies spaced arms 12 which have their free ends positioned between the offset portion 7 of the arm 6, where the same have pivotal connection with the arm 6, as by means of the pivot pin 13.

The jaw 8 is also pivotally supported between the arms 12 of the jaw 11, as by means of the pivot pin 14, so that as pressure is brought to bear on the handle 5 of the wrench, the jaw 8 may pivot or move to automatically adjust itself into gripping relation with the article under operation, which in the present drawing is in the form of a pipe indicated at 15.

From the foregoing, it will be seen that due to the elongated opening 9 and the construction of the pin 10, the jaw 8 will be permitted to move to a degree to adjust itself independently of the movement of the handle 5.

In the use of the device, the jaws are positioned around an article to be removed, and pressure is brought to bear on the handle portion 5, causing the handle portion 5 to pivot at 13 and move the jaw 8 into close engagement with the article under operation.

It is obvious that as the pressure on the handle 5 is increased, the gripping action of the jaws 8 and 11 is also increased, and slipping of the wrench with respect to the article is absolutely prevented.

What is claimed as new is:—

A wrench including a handle portion having spaced arms, the free ends of the arms being formed with offset portions, a jaw having an elongated opening, a pivot pin connecting the arms and passing through the elongated opening to connect the jaw to the handle, an outer jaw including spaced arms, the ends thereof having connection with the arms of the handle portion at the offset portions thereof, the first mentioned jaw being pivotally supported between the spaced arms of the outer jaw, and teeth formed on the jaws.

In testimony that I claim the foregoing as my own, I have hereto affixed my signature in the presence of two witnesses.

WALTER L. BOCKOVER.
